US0D1008736S

(12) **United States Design Patent** (10) **Patent No.:** **US D1,008,736 S**
(45) **Date of Patent:** **** Dec. 26, 2023**

(54) **COMBINED DRINKING WATER BOTTLE
AND BODY SPRAY NOZZLE**

(71) Applicant: **RiViv, LLC**, Tucson, AZ (US)

(72) Inventor: **Skye Forrest**, Tucson, AZ (US)

(73) Assignee: **RiViv, LLC**, Tucson, AZ (US)

(**) Term: **15 Years**

(21) Appl. No.: **29/783,482**

(22) Filed: **May 13, 2021**

(51) LOC (14) Cl. **09-01**

(52) U.S. Cl.
